Patented June 20, 1905.

UNITED STATES PATENT OFFICE.

MAX R. LEHMAN, OF QUINCY, ILLINOIS, ASSIGNOR TO EXCELSIOR STOVE
& MANUFACTURING COMPANY, OF QUINCY, ILLINOIS, A CORPORATION.

DESIGN FOR A HEATING-STOVE.

SPECIFICATION forming part of Design No. 37,470, dated June 20, 1905.

Application filed May 16, 1905. Serial No. 260,682. Term of patent 7 years.

To all whom it may concern:

Be it known that I, MAX R. LEHMAN, a citizen of the United States, residing in Quincy, in the county of Adams and State of Illinois, have invented a new, useful, and ornamental Design for Heating-Stoves.

The accompanying drawing, which is a perspective view, illustrates my new, original, and ornamental design for a heating-stove.

I claim—

The ornamental design for a heating-stove,
as shown.

MAX R. LEHMAN.

In presence of—

A. J. ROBINSON,
J. B. ULLMEN.
